F. Schottländer

UNITED STATES PATENT OFFICE.

JAMES LITTLE NEILSON, OF WINNIPEG, MANITOBA, CANADA,

GRAIN DOOR.

Application filed September 25, 1923. Serial No. 664,727.

To all whom it may concern:

Be it known that I, JAMES LITTLE NEILSON, a subject of the King of Great Britain, and resident of the city of Winnipeg, in the 5 Province of Manitoba, Canada, have invented certain new and useful Improvements in Grain Doors, of which the following is the specification.

The invention relates to improvements in 10 grain doors and an object of the invention is to provide a strong and durable door which will effectively hold the pressure of the grain in the car and which is comparatively light so that the same can be readily 15 manipulated when opening and closing or stacking.

A further object is to construct a grain 20 tight door which can be readily placed in the car and locked in the closed position and which is arranged such that the attendant can easily and quickly unlock the same to free the door to open under the pressure of the grain.

A still further object is to provide a door 25 which can be adjusted in width to accommodate the varying widths of doorway openings and which is attached to the door posts in a manner such that it can be raised towards the roof of the car or can be swung 30 inwardly and stacked against the inner wall of the car when not in use.

A further object is to construct a grain 35 door from sections which converge inwardly of the car and have their outer ends butted 40 against the posts and their meeting ends detachably fastened together, whereby the door is in the form of a truss and the outward pressure of the grain is transmitted through the truss so formed to the posts, such latter construction also providing ample foot room on the door sill for the attendant.

With the above more important objects 45 in view the invention consists essentially in the arrangement and construction of parts hereinafter more particularly described and later pointed out in the appended claims, reference being had to the accompanying drawings in which:

Fig. 1 is an exterior view of a car 50 equipped with my door.

Fig. 2 is an interior view of the parts appearing in Fig. 1.

Fig. 3 is an enlarged detailed horizontal 55 sectional view at 3-3' Fig. 1.

Fig. 4 is an enlarged detailed vertical sectional view at 4-4' Fig. 1.

Fig. 5 is an enlarged detailed horizontal sectional view through one side of the door and the adjoining post.

Fig. 6 is an enlarged detailed horizontal sectional view through the central part of the door, the section being taken in the same plane as at 3-3' Fig. 1.

Fig. 7 is an enlarged detailed horizontal 65 sectional view through a portion of the door and the adjoining post.

Fig. 8 is a vertical sectional view at 8-8' Fig. 6.

Fig. 9 is a perspective view of one of the 70 straps and parts adjoining the same as they appear on the door.

Fig. 10 is a sectional view at 10-10' Fig. 1.

In the drawings like characters of reference 75 indicate corresponding parts in the several figures.

The grain car 1 presents the customary door posts 2 and 3, door sill 4 and lintel 5, the latter parts bounding the doorway opening 6.

The grain door which I provide comprises two similar right and left sections 7 and 8, the sections being shown in the present instance as formed from metallic plates, 85 preferably sheet steel. The inner ends of the plates are bent at an obtuse angle to provide end wings 9 and 10 which are positioned one in front of the other when the door is closed. The free edges of the wings 90 are turned backwardly on themselves, as indicated at 11 and 12, for strengthening purposes, and to each section I permanently fasten, as by riveting, vertically disposed straps or bars 13 and 14 which are adapted 95 to engage with the turned edges 11 and 12 of the wings.

The doorway openings of grain cars vary in width and on this account I have fitted my door with similar right and left extension plates 15 and 16 which are of the full height of the sections and are adjustably secured to the outer ends of the sections by adjusting bolts 17 carried by the sections and operating in suitable horizontally disposed slots 18 formed in the extensions. The edges of the extension plates are turned backwardly on themselves, as indicated at 19 and 20, to strengthen the edges thereof and the outer edges of the extension plates 110

are adapted to engage with the edges of metallic plates 21 and 22 fastened to vertical strips 23 and 24 secured to the door posts.

- 5 It will be here observed that the strips 23 and 24 are somewhat narrower than the posts so that they provide in each instance two right angled corners 25 and 26 extending upwardly at the inner side of each post.
- 10 To the outer end of each extension I secure a pair of hinges 27 and 28, each hinge having a leaf 29 riveted to the extension and a leaf 30 shaped to span the upright strip and plate secured to the adjacent post. The 15 edge of the extension is cut away in each instance to permit the leaf 30 to pass through (see Fig. 7) and the hinge joint in each instance butts into the corners 25 when the door is in closed position. In this way the 20 outer ends of the door sections are butted against the inner edges of the vertical strips and plates.

The free ends of the leaves 30 of the hinges are hooked, as indicated at 31, to catch 25 around a vertically disposed guide rod 32 associated with each post and located in the corners 26 aforesaid. The rods 32 are carried in upper and lower sockets 33 and 34 secured to the floor and roof of the car and 30 provision is made so that the rods can be removed if desired.

From the above arrangement it will be obvious that the rods will serve to vertically 35 guide the door sections if they be lifted and that the hooks 31, co-acting with the rods, will serve to form pivots around which the door sections can be swung to pass them to a stored position against the inner walls of the car. It will be noted also that should 40 the door sections be turned to such stored position they can be removed, as the hooks will then withdraw inwardly from the rods. Adjustable collars 35 are mounted on the rods directly beneath the lower hinges and 45 can be adjusted to permit the door sections to swing clear of the car floor. These collars are not necessary, but can be utilized if provision is made for preventing leakage of grain between the lower edges of the sections and the floor. In the present instance 50 I have shown the collars as used and have provided the lower edge of each door section with a flexible canvas strip 36 which is fastened to the door section by a metallic bar 37 crossing one edge of the strip and suitably riveted to the door section.

The inner lapped ends 9 and 10 of the door sections are provided with means for releasably locking them together when the 60 door is in the closed position. Such is now described in detail:

To the inner wing 9 I permanently fasten 65 similar upper and lower vertically aligned eyes 38, the eyes extending through horizontal slots 39 provided in the wings 10.

Upper and lower vertically aligned straps 40 and 41 are secured permanently to the wing 10 and these straps receive slidably the upper and lower ends of locking bolts 42 and 43, the bolts being adapted also to be extended through the eyes and in so doing lock the wings of the sections together. The inner ends of the locking bolts are pivotally connected to a disc 44 pivotally attached to the outer wing 10 and the disc is supplied with 70 an extending handle 45 whereby the same can be manipulated. Obviously, when the handle is raised the locking bolts will be withdrawn from the eyes and accordingly the eyes will be released to escape through the slots 39. The wing 10 is supplied with a wedge shaped catch 46 and the handle is adapted to operate over this catch and engage with the large end thereof to lock the handle against movement when the bolts are 75 80 85 in the locked position.

Referring more particularly to Fig. 3, it will be seen that the door is in the form of a flattened V-shaped truss extending inwardly into the grain and arranged such that the 90 outward pressure of the grain is taken up by the posts, which act as abutments. I wish to draw particular attention to this truss-like arrangement and to the manner in which the door is constructed to carry the various 95 stresses to the posts.

In this connection I may say that I am aware that double doors are used, the door sections lying in parallel planes and being 100 detachably fastened together and having their ends resting against the door posts. In such an arrangement, however, the outward pressure of the grain is very hard on the joint as the door posts simply act as fulcrums for the door sections. According to 105 my construction, however, the door posts act as abutments and the outward pressure of the grain serves simply to press the outer ends of the sections more tightly into the corners 25.

When it is desired to open the door one simply pulls the handle 45 outwardly to clear the end of the catch 46 and then forces the handle upwardly. This withdraws the 110 bolts from the eyes and allows the inner edges of the door sections to swing outwardly through the doorway opening and permit the grain to flow freely from the car.

Whilst I have described the door as 115 formed entirely of metal, I wish it to be understood that I do not wish to be limited to this particular material as a wood door could be made embodying the features of the invention.

What I claim as my invention is:

1. The combination with the door posts of a grain car, of a grain door formed from a pair of sections converging inwardly of the car and having their outer ends butted against the posts and their inner ends lap-

ping, a vertical strip secured to the inner end of each section and abutting the adjacent end of the other section and means for releasably locking the lapped ends of the 5 sections together.

2. The combination with the door posts of a grain car, of a grain door formed from a pair of sections converging inwardly of the car and having their outer 10 ends butted against the posts and their inner ends lapping, a vertical strip secured to the inner end of each section and abutting the adjacent end of the other section, eyes carried by the inner lapped end and 15 projecting through suitable slots provided in the lapping end of the other section, locking bolts carried by the latter section and engageable with the eyes to lock the sections together, and lever controlled 20 means for simultaneously shifting the bolts.

3. The combination with the door posts of a grain car, of vertically disposed strips secured to the inner faces of the posts, said strips having their edges set back from the 25 edges of the posts, a grain door formed from two similar sections converging inwardly of the car and having their outer ends engaging the posts and butted against the strips and their inner ends lapping, 30 means releasably locking the lapped ends of the sections together, vertically disposed stationary guide rods located to the outer sides of the strips and hinges attached to the outer ends of the door sections, said 35 hinges each embodying a wing permanently fastened to the section and a wing strad-

dling the adjacent strip and provided with a hooked extremity slidably caught and pivotally mounted on the adjacent guide rod.

4. In a door structure, the combination 40 with a pair of door posts, of the pair of strips secured to the outer surface of the posts and made of less width than the latter so that the sides of each strip are spaced inwardly from the corresponding sides of 45 its respective post to provide vertically extending shoulders, a pair of door sections arranged in truss formation with the outer vertical edges of the door sections engaging the inner sides of said strips, the inner edges 50 of said door sections being bent at an acute angle to the body portions of the sections and disposed in overlapping engagement, means for locking said overlapping portions together, a guide rod mounted to extend 55 vertically adjacent the outer side of each strip and a plurality of hinges carried by the outer edge portion of each door section, each hinge having one leaf rigidly fastened to the door section and the other leaf shaped 60 to embrace the outer and side surfaces of the adjacent strip, the free extremity of said leaf being hooked about the guide rod at the outer side of the strip so as to be capable of swinging and sliding movement 65 on said rod.

Signed at Winnipeg, this 3rd day of September 1923.

JAMES LITTLE NEILSON.

In the presence of:

GERALD S. ROXBURGH,
W. C. BOGESS.
